UNITED STATES PATENT OFFICE.

FRÉDÉRIC GRAEF, OF PARIS, FRANCE.

VEHICLE-SHAFT.

SPECIFICATION forming part of Letters Patent No. 738,673, dated September 8, 1903.

Application filed November 7, 1902. Serial No. 130,434. (No model.)

To all whom it may concern:

Be it known that I, FRÉDÉRIC GRAEF, a citizen of the French Republic, residing at 203 Rue Lafayette, Paris, France, have invented 5 certain new and useful Improvements in Vehicle-Shafts, of which the following is a specification.

My invention relates to shafts for all kinds of vehicles requiring such appendages, and 10 has for its object to provide improved devices of this character which will not be liable to be broken when the animal harnessed to the vehicle falls upon them or by any other analogous accident.

15 With this object in view the invention consists in the improved construction, arrangement, and combination of the parts of vehicle-shafts hereinafter fully described and afterward specifically claimed.

20 In the accompanying drawings, which illustrate my invention, Figure 1 is a view, partly in elevation and partly in longitudinal section, of parts of the two sections of a shaft separated from each other. Fig. 2 is a similar 25 view, the section being on a plane at a right angle to that of Fig. 1. Fig. 3 is a view of small portions of the two sections of the shaft joined together. Fig. 4 shows, respectively, 30 on the left and right end elevations of the rear and front sections of the shaft.

Like letters of reference mark the same parts in all of the figures.

Referring to the drawings by letters, *a* and *b* indicate the rear and front sections of a shaft, 35 respectively. In a bore in the end of the section *a* is inserted a socket *c*, in which are

mounted two latch-springs *d* and *e*, adapted to receive when the sections *a* and *b* are pressed together the arrow - headed pin *f*, which projects from a plate *g*, secured by 40 screws or otherwise in the end of the section *b*. By this means the two sections *a* and *b* will be held together during all ordinary uses, but will come apart when extra strain is brought upon the joints. In order to prevent any 45 twisting movement of the joint, dowel-pins *h* and *i*, projecting from the end of the section *a*, engage in holes in the plate *g*, as shown in Fig. 2. The pressure of the animal in falling will tend to separate the sections *a* and *b*, 50 thus reducing the liability of breakage.

It is obvious that each shaft may be made in as many such jointed sections as is found desirable.

Having thus fully described my invention, 55 what I claim as new, and desire to secure by Letters Patent of the United States, is—

A vehicle - shaft comprising a plurality of sections joined end to end, a socket in the meeting end of one section, latch - springs 60 mounted in said socket, an arrow-pointed pin projecting from the meeting end of the adjoining section in line with and adapted to engage between the latch-springs, and means for preventing twisting movement of the joint, 65 substantially as described,

In testimony whereof I affix my signature in presence of two witnesses.

FRÉDÉRIC GRAEF.
